(57) **CLAIM**

The ornamental design for a cooler assembly, as shown and described.

DESCRIPTION

FIG. 1 is a front and left perspective view of a cooler assembly showing our new design;

FIG. 2 is a left side view thereof;

FIG. 3 is a right side view thereof;

FIG. 4 is a rear plan view thereof;

FIG. 5 is a front view thereof;

FIG. 6 is a top view thereof;

FIG. 7 is a bottom view thereof;

FIG. 8 is a front and left perspective view of a cooler assembly showing a second embodiment of our new design;

FIG. 9 is a left side view thereof;

FIG. 10 is a right side view thereof;

FIG. 11 is a rear plan view thereof;

FIG. 12 is a front view thereof;

FIG. 13 is a top view thereof; and

FIG. 14 is a bottom view thereof;

FIG. 15 is a front and left perspective view of a cooler assembly showing a third embodiment of our new design;

FIG. 16 is a left side view thereof;

FIG. 17 is a right side view thereof;

FIG. 18 is a rear plan view thereof;

FIG. 19 is a front view thereof;

FIG. 20 is a top view thereof; and,

FIG. 21 is a bottom view thereof.

(Continued)

The broken lines in broken lines depict portions of the cooler assembly that form no part of the claimed design. All unshaded surfaces between solid and broken lines form no part thereof.
